UNITED STATES PATENT OFFICE

MALCOLM J. WENNERSTROM, OF MINNEAPOLIS, MINNESOTA

ANCHOR-MANIPULATING APPARATUS

Application filed May 31, 1930. Serial No. 458,652.

This invention relates to anchor elevating and controlling devices for boats and particularly to such devices for the convenient use of fishermen.

5 It is an object of my present invention to provide a comparatively simple anchor controlling device wherein a guide or davit is provided at one end of the boat and associated with a conveniently located reel or winding device and wherein provision is made for positively holding the reel against rotation and for braking or checking the unwinding of the reel when the weight of the anchor is upon the anchor cable.

10 15 A further object is to provide a compact, portable device of the class above described wherein the davit and the reel are provided for quick attachment to convenient parts of common types of boats.

20 25 Another object is to provide in an anchor controlling device, a davit or over-hanging guiding means associated with a reel or winding device and means associated with said davit and the anchor for preventing the anchor from striking the side of the boat when it is in raised position.

Still a further object is to provide in such a device, a reel or winding device which is capable of attachment to various parts of a boat and which is provided with a cable guide which enables the anchor cable to be properly guided to the reel regardless of whether the reel is positioned to rotate on a vertical or horizontal axis.

25 30 These and other objects will be apparent from the following description, wherein like reference characters refer to similar parts throughout the several views, and wherein:—

35 Fig. 1 is a perspective view showing the forward portion of a row boat with an embodiment of my invention attached thereto;

40 Fig. 2 is a top plan view of the winding reel detachably secured to one of the seats of the boat;

Fig. 3 is a vertical section taken on the line 3—3 of Fig. 2;

Fig. 4 shows a side elevation of the davit and anchor engaging plate or means for holding the anchor in the raised position 50 spaced from the side of the boat;

Fig. 5 is a cross section taken on the line 5—5 of Fig. 4 showing the manner in which my anchor engaging plate is attached to the davit, and

55 Fig. 6 is a cross section taken on the line 4—4 of Fig. 4.

In the drawings an embodiment of my invention is shown detachably applied to a row boat of standard construction having the usual gunwale G, rowing seat S and a short deck portion D at the bow which is defined at its inner edge in the usual manner by the upstanding board or flange F.

60 My device includes a short davit 7 which has a base portion secured to a clamping bracket 8, said clamping bracket being of U-shape in cross section and adapted to engage the gunwale of a boat or the flange F and having a clamping screw 9 threadedly connected with one of the prongs of the U. The base of davit 7 may be connected with the horizontal top of bracket 8 for attachment in two or more positions. This may be accomplished by providing a vertical bolt 10 which extends through the flanged base of the davit and threadedly engages the attachment and the base of the davit is also provided with a depending dowel 11 which is adapted to engage sockets 12 formed in the upper surface of the attachment bracket. A pulley or other suitable guide 13 is swivelly attached to the outer end of the davit and the anchor cable 14 extends through the sheave of pulley 13 and is connected with the winding drum 80 of my reel.

85 My winding reel is rotatably connected with a strong attachment bracket indicated as an entirety by the numeral 15, said bracket having a U-shaped clamping portion pro-

vided with a clamping screw 15a for facilitating attachment of the winding reel to a seat or the gunwale of a boat. Attachment bracket 15 includes an outwardly projecting 5 boss 15b having a concentric socket therein to which the winding drum 16 is pivotally secured. As shown, I provide a pivot pin in the form of a bushing 17 which may extend through the hub of drum 16 with its 10 inner end driven into the socket within the boss 15b and a bolt 18 extends through bushing 17 with its inner end threadedly connected with the boss portion 15b of the attachment bracket, a washer being interposed 15 between the outer end of bolt 18 and the hub of drum 16. My winding drum has a relatively deep peripheral groove on which the anchor cable 14 is wound and a crank handle 19 is attached to one of the flanges of the 20 drum at a point adjacent the peripheral edge thereof.

A guiding arm 20 is pivotally mounted on the bushing 17 and interposed between the inner end of winding drum hub 16 and the 25 boss 15b of the attachment bracket. This guide is in the form of an arm having an upturned eye 20a through which the cable 14 extends and it will be noticed that the arm of the guide may swing upon the bushing 30 into a position in alignment with the pulley 13 attached to the davit.

The inner flange numbered 16a, of the winding drum, is provided with a series of spaced notches 16b in its peripheral edge, 35 which notches are adapted to be engaged by the tooth 21a of a pawl 21, said pawl being pivoted by a pin 22 to a portion of the attachment bracket 15 which underlies the edge of the drum. It will be noticed that the 40 pawl 21 has a U-shaped end, the intermediate portion of which is pivoted by the pin 22 on an axis extending at right angles to the axis of rotation of the drum and that the tooth 21a is formed adjacent the handle or 45 outer end of the pawl, while at the inner end of the U-shaped portion of the pawl a braking arm 21b is located adapted to frictionally engage the inner periphery of the rim of the winding reel which rim constitutes a brake 50 drum. A coiled spring 23 is interposed between the outer portion of the pawl 21 and an abutment 15c carried by the clamping portion of bracket 15.

The letter A designates a suitable type of 55 anchor which may be detachably connected to the outer end of anchor cable 14 by suitable means, such as a split hook and this anchor has a shank which is adapted when the anchor is raised to be surrounded and confined by a 60 keeper plate 24. Plate 24 has an attachment portion 24a which is provided with a pair of spaced apertures therethrough through which the davit-securing bolt 10 and the davit 65 dowel 11 may extend and said attachment portion is interposed between the base of the

davit and the upper surface of the davit attachment bracket 8. The outer portion of plate 24 is off-set below the attachment portion and terminates in an annular confinement member 24b of internal diameter suitable to surround the shank of the anchor and prevent the anchor from swinging when disposed in raised position. 70

Operation 75

As illustrated in the drawings, the davit is detachably secured to the flange F at the bow of the boat extending outwardly from one of the longitudinal sides of the boat and the winding reel is detachably secured to one of the rowing seats S. It will of course be understood that the davit may be secured conveniently to any vertical edge, such as the gunwale G, and that the winding reel may also be secured to a portion of the gunwale 80 with the axis of rotation disposed in horizontal position. The guide 20 for the winding reel will automatically be swung into alignment with the pulley 13 of the davit by anchor cable 14 and when it is desired to lower the anchor it is only necessary to depress the handle of pawl 21 slightly, thereby releasing engagement between the tooth 21a and the cooperating peripheral edge of the winding drum. Gravity will of course pay 85 out the anchor cable and if the anchor is dropping at too fast a speed, the speed may be checked by further depression of the handle of pawl 21, this action causing the braking arm 21b to frictionally engage the inner periphery of the braking drum. When pawl 21 is released engagement between the tooth 21a and the notches 16b of the drum will again be effected and the drum will be locked 90 against further unwinding. 95

To hoist the anchor it is only necessary to turn the winding reel by means of the crank handle 19, the notches 16b slipping over the tooth 21a of the spring-pressed pawl. The upper end of the anchor shank will be guided 100 through the keeper plate 24 and when the anchor is in fully raised position, will be confined and prevented from swinging and knocking against the side of the boat. 105

It will be seen that by releasing fastening bolt 10 the davit and keeper plate 24 may be disposed in outwardly projecting position on the opposite side of the boat. Both the davit and winding reel may thus be attached, readily, to either the right or left side of the boat, as found most convenient by the user and the attachment brackets of said members are adapted to cooperate with any suitable flange or board, within, of course, certain limits as to thickness but regardless of whether the supporting member is disposed in a vertical or horizontal plane. 115

My efficient cable guide 20 associated with the winding reel positively assures accurate feeding of the cable upon the reel and is self- 120 125 130

adjustable and self-aligning with the pulley of the davit due to its swingable mounting upon the boss 15b of the attachment bracket 15.

- 5 In the foregoing description it will be seen that I have provided a highly efficient, compact and portable anchor-manipulating device, capable of wide general use and especially adapted for fishing boats and enabling 10 a fisherman to conveniently raise or lower his anchor without moving from the rowing seat or other portion of the boat wherein he is sitting.

It will, of course, be understood that various changes may be made in the form, details, proportions and arrangement of the parts without departing from the scope of applicant's invention, which, generally stated, consists in a device capable of carrying 20 out the objects above set forth, and in the novel parts and combinations of parts disclosed and defined in the appended claims.

What is claimed is:—

1. In anchor manipulating apparatus, a 25 winding device including a support, a reel rotatably mounted on said support and having affixed thereto one end of an anchor cable, said reel including an annular element provided with retaining elements and a 30 lever pivoted to said support and having cooperating retaining elements for positively holding said reel against unwinding, said lever also having a rigidly connected braking arm adapted to frictionally engage a portion 35 of said reel to check the speed of unwinding thereof when said lever is swung to a predetermined position.

2. In anchor manipulating apparatus, an attachment bracket constituting a support, a 40 winding reel pivotally mounted on said bracket, an anchor cable, one end of which is fixed to said reel, said reel having an annular flange provided with a series of spaced retaining elements, said reel also having a cylindrical periphery constituting a braking drum and a lever pivoted to said attachment bracket having a tooth which normally cooperates with said retaining elements to positively hold said reel against unwinding, said 45 lever also having an integrally formed brake arm adjacent one end thereof adapted to frictionally engage said brake drum when said lever is swung to a predetermined position.

3. In anchor manipulating apparatus, an 55 attachment bracket constituting a support, a winding reel pivotally mounted on said bracket, an anchor cable, one end of which is fixed to said reel, said reel having an annular flange provided with a series of spaced retaining elements, said reel also having a cylindrical inner periphery constituting a braking drum, a lever pivoted to said attachment bracket adjacent said reel, said lever having an arm, a portion of which constitutes a handle, said arm having a tooth adapted to co-

operate with the retaining elements of said annular flange to permit said reel to be wound and to normally positively prevent unwinding of said reel, said lever having a second arm disposed normally inwardly of 70 and in juxtaposition to said braking drum and means for yieldingly holding said lever in position with said tooth engaging said retaining elements.

4. In anchor manipulating apparatus, an 75 attachment bracket constituting a support, a winding reel pivotally mounted on said bracket and having affixed thereto one end of an anchor cable, a davit spaced some distance from said winding reel through which said cable passes, means for retaining said reel against unwinding and a guide pivotally connected with said reel attachment bracket and swinging on an axis concentric with the axis of said reel, said guide having 80 an eye opposed to the exterior periphery of said reel whereby said eye will be self-aligning with said davit.

5. In anchor manipulating apparatus, an 85 anchor bracket constituting a support, a winding reel pivotally mounted on said bracket, an anchor cable, one end of which is fixed to said reel, a davit mounted at some distance from said reel through which said anchor cable extends, a pivot member for 90 said reel having its inner end fixed to said attachment bracket and a guide member pivotally mounted on said pivot member and interposed between said reel and said attachment bracket and having an up-turned 95 eye opposed to the winding periphery of said reel and adapted to be self-aligning with said davit.

6. In anchor manipulating apparatus, a 100 winding reel adapted to be attached to a portion of a boat, a davit also adapted to be attached to said boat at a point removed from said winding reel, said davit having a guide out-rigged with regard to the gunwale of the boat, an anchor cable extending 105 through said guide having one of its ends secured to said reel, an anchor having a straight shank secured to the other end of said cable and an out-rigged confining element mounted on said davit and substantially 110 vertically aligned with said guide through which the shank of said anchor is adapted to pass when the anchor is raised, to prevent 115 the anchor from striking against the side of the boat.

7. The structure set forth in claim 6, wherein in said anchor confining member comprises a plate interposed between the base of said davit and its attachment bracket and wherein the outwardly projecting portion of said 120 plate has an annular element for surrounding the shank of said anchor.

8. In anchor manipulating apparatus, an 125 attachment bracket constituting a support, a winding reel pivotally mounted on said

bracket and having affixed thereto one end of an anchor cable, a davit spaced some distance from said winding reel through which said cable passes, means for retaining said reel against unwinding and a guide pivotally connected with said reel attachment bracket on a substantially vertical axis, said guide having an eye opposed to the exterior periphery of said reel whereby said eye will be self-aligning with said davit.

18 In testimony whereof I affix my signature.
MALCOLM J. WENNERSTROM.
